(57) **CLAIM**

The ornamental design for a shaker, as shown and described.

DESCRIPTION

FIG. 1 is an isometric view of a shaker according to one embodiment of the present invention

FIG. 2 is a front elevation view thereof;

FIG. 3 is a right side elevation view thereof;

FIG. 4 is a left side elevation view thereof;

FIG. 5 is a cross sectional view taken along line 5-5 of FIG. 2;

FIG. 6 is a cross sectional view taken along line 6-6 of FIG. 2;

FIG. 7 is a top plan view thereof; and

FIG. 8 is a bottom plan view thereof.

FIG. 9 is an isometric view of a shaker according to a second embodiment of the present invention;

FIG. 10 is a front elevation view thereof;

FIG. 11 is a right side elevation view thereof;

FIG. 12 is a left side elevation view thereof;

FIG. 13 is a cross sectional view taken along line 13-13 of FIG. 10;

FIG. 14 is a cross sectional view taken along line 14-14 of FIG. 10;

FIG. 15 is a top plan view thereof; and,

FIG. 16 is a bottom plan view thereof.

The broken lines in the drawings depict portions of the shaker that form no part of the claim.

The gradated stippling around the display screen in the drawings is for shading purposes to show contours and is not intended to represent texture.

1 Claim, 16 Drawing Sheets
